UNITED STATES PATENT OFFICE

EDWIN PRESTAGE, OF LONDON, ENGLAND, ASSIGNOR OF ONE-HALF TO BROOM & WADE LIMITED, OF HIGH WYCOMBE, BUCKINGHAMSHIRE, ENGLAND, A COMPANY OF GREAT BRITAIN

HIGH PRESSURE GAS COMPRESSOR

Application filed September 25, 1930, Serial No. 484,377, and in Great Britain July 21, 1930.

The present invention relates to improvements in those high pressure gas compressors described in United States patent application Ser. No. 435,246, in which a sleeve valve is arranged between the piston and the cylinder and reciprocated in a partly contrary direction to the piston. In the compressors described in these patent specifications the discharge ports for the gas are formed in the sleeve valve above the suction ports and these ports co-act with a valve or a series of valves set behind or above these ports but actually on the sleeve. The above valve arrangements have been found very satisfactory in those high pressure gas compressors in which water jackets are not used.

In certain cases it is necessary to provide water cooling means, particularly in those compressors designed for compressing air and in some classes of refrigerating machines.

The high speed valve compressor forming the present invention allows of the point of discharge through the automatic valve or valves taking place much later in the stroke than hereto possible, so that the velocity of discharging gas is lower than in any other type of compressor running at the same piston speed. Further, the present machine is designed to present a large cooling surface to the gas or air passing through the machine during the compression stroke.

Briefly stated the present invention comprises a sleeve valve compressor in which the compressed air or gas passes from the cylinder into a channel or annulus at the end of the compression stroke and is trapped in said annulus and then expelled therefrom by the upward movement of the sleeve.

My invention is illustrated by way of example in the accompanying drawing which shows a sectional elevation of the compressor cylinder with a portion of the junk ring and cylinder head in full.

Referring now to the drawing, a sleeve 1 with inlet ports 2 is reciprocated within the cylinder 3 in a partly contrary direction to the piston 4. During the down stroke of piston 4 the sleeve 1 moves upwards bringing the ports 2 in line with slot 5 which is

machined through cylinder wall into suction annulus 6 which is connected in turn with the atmosphere or gas inlet pipe through opening 7. When the piston 4 reaches the bottom of its stroke the sleeve 1 cuts off ports 2 from communicating with the cylinder and compression of the contained air or gas proceeds as the piston 4 moves upward. At about half stroke the top of sleeve 1 comes below the cut off edge of piston or junk ring 8 thereby allowing the air or gas undergoing compression to flow into the annulus 9 formed by the cylinder 3 and cylinder head 10. When the piston 4 reaches the top of its stroke, the top of the sleeve 1 which has been moving upwards across the recessed part of the piston or junk ring 8 comes on to the lip of this ring and thereby shuts off all communication between the cylinder 3 and annulus 9 where compressed air or gas is trapped. As the piston 4 moves downward on its next suction stroke, the top of the sleeve 1 moves upwards into the annulus 9 pushing the air or gas in this space up through the valve or valves 11 which are resting on the seat 12. As stated the gas is admitted to the cylinder through the lower ports 2 in the sleeve as the piston descends, which ports are shut owing to the downward travel of the sleeve when the piston reaches the bottom of its stroke. During the upward or compression stroke of the piston the top of the sleeve moves down below the recessed piston ring 8 on the cylinder head. The top of the sleeve comes below the cut off edge of the piston ring 8 at about half stroke, and by exposing to the cylinder the annulus 9 in which it reciprocates, allows the air or gas in process of compression to expand into this space.

In this manner a relatively long narrow water cooled channel is provided for the air or gas just at the critical moment when the greatest heat is being generated by compression, which results in the compression being much nearer isothermal than would otherwise be the case. Just as the piston reaches the top of its stroke the top of the sleeve, which is now moving upward, cuts off on the edge of said piston or junk ring 100

8 on the cylinder head, thus effectually preventing the return of any air or gas trapped in the annulus 9 above the sleeve. The compressed air is then discharged by the upward motion of the sleeve through the 5 automatic valve or valves in the housing above at a low velocity. These valves close when the sleeve reaches the top of its stroke thus preventing any return of the expelled 10 gas or air. It should be understood that a series of feather valves or ball valves may be seated in the housing above the sleeve instead of the plain ring valve as shown. This outlet valve or valves 11 is/are mounted 15 in a cage or housing 13 surrounding the cylinder head and resting on the cylinder 3 in such a position that the valves are just above the top of the sleeve when this is on the top of its stroke. The tension 20 springs 14 beneath the cylinder cover, hold the valve seat firmly down in its position above the cylinder 3. The cylinder and cylinder head are provided with water jackets 15-16 so that a large cooling surface 25 is presented to the air or gas passing through the machine.

What I claim is:—

1. A high pressure air or gas compressor comprising a cylinder with gas inlets spaced 30 around its wall, a piston reciprocating in said cylinder, a cylinder head projecting into said cylinder and of such a diameter that it forms with the inner wall of the upper end of the cylinder an annulus, a housing 35 at the upper end of said annulus, an automatic outlet valve in said housing and a sleeve valve reciprocating in said cylinder between said piston and cylinder head and the inner wall of said cylinder in a partly contrary direction to said piston and adapted 40 to first trap the air or gas compressed into said annulus on the upward stroke of the piston and then to expel said air or gas therefrom through the outlet valve on its continued upward movement through said annulus.

2. A high pressure air or gas compressor comprising a cylinder with gas inlets spaced 50 around its wall, a piston reciprocating in said cylinder, a cylinder head projecting into said cylinder and of such a diameter that it forms with the inner wall of the upper end of the cylinder an annulus, a housing 55 at the upper end of said annulus, an automatic outlet valve in said housing, a sleeve valve reciprocating in said cylinder between said piston and cylinder head and the inner wall of said cylinder in a partly contrary direction to said piston and adapted 60 to first trap the air or gas compressed into said annulus on the upward stroke of the piston and then to expel said air or gas therefrom through the outlet valve on its continued upward movement through said 65 annulus and a recessed junk ring surround-

ing the projecting end of said cylinder head adapted to co-act with said sleeve valve to trap the compressed air or gas in said annulus before it is expelled therefrom by said valve.

3. A high pressure air or gas compressor comprising a cylinder with gas inlets spaced around its wall, a piston reciprocating in said cylinder, a cylinder head projecting into said cylinder and of such a diameter 70 that it forms with the inner wall of the upper end of the cylinder an annulus, a housing at the upper end of said annulus, an automatic outlet valve in said housing, water chambers in said cylinder head and cylinder adapted to present a large cooling surface 75 to said annulus and a sleeve valve reciprocating in said cylinder between said piston and cylinder head and the inner wall of said cylinder in a partly contrary direction to said piston and adapted to first trap the air or gas compressed into said annulus on the upward stroke of the piston and then to expel said air or gas therefrom through the outlet valve on its continued upward 80 movement through said annulus.

4. A high pressure air or gas compressor comprising a cylinder with gas inlets spaced around its wall, a piston reciprocating in said cylinder, a cylinder head projecting into 90 said cylinder and of such a diameter that it forms with the inner wall of the upper end of the cylinder an annulus, a housing surrounding said cylinder head at the upper end of said annulus, a ring valve positioned in said housing just above the top of said sleeve valve when this is at the top of its stroke, springs adapted to hold said valve down on its seating in said housing, a sleeve valve reciprocating in said cylinder between 95 said piston and cylinder head and the inner wall of said cylinder in a partly contrary direction to said piston and adapted to first trap the air or gas compressed into said annulus on the upward stroke of the piston and then to expel said air or gas therefrom through the outlet valve on its continued upward movement through said annulus.

5. A high pressure air or gas compressor comprising a cylinder with gas inlets spaced 100 around its wall, a piston reciprocating in said cylinder, a cylinder head projecting into said cylinder and of such a diameter that it forms with the inner wall of the upper end of the cylinder an annulus, a housing 105 surrounding said cylinder head at the upper end of said annulus, a ring valve positioned in said housing just above the top of said sleeve valve when this is at the top of its stroke, springs adapted to hold said valve down on its seating in said housing, water chambers in said cylinder head and cylinder adapted to present a large cooling surface to 110 said annulus, a sleeve valve reciprocating in said cylinder between said piston and cylinder 115 adapted to first trap the air or gas compressed into said annulus on the upward stroke of the piston and then to expel said air or gas therefrom through the outlet valve on its continued upward movement through said annulus.

der head and the inner wall of said cylinder in a partly contrary direction to said piston and adapted to first trap the air or gas compressed into said annulus on the upward stroke of the piston and then to expel said air or gas therefrom through the outlet valve on its continued upward movement through said annulus and a recessed junk ring surrounding the projecting end of said cylinder head adapted to co-act with said sleeve valve to trap the compressed air or gas in said annulus before it is expelled therefrom by said valve.

In testimony whereof I have signed my name to this specification.
